FREQUENCY MODULATION

La Verne R. Philpott, Washington, D. C.

Application November 12, 1937, Serial No. 174,212

13 Claims. (Cl. 179—171.5)

(Granted under the act of March 3, 1883, as
amended April 30, 1928; 370 O. G. 757)

This invention relates to a vacuum tube network for obtaining frequency modulation of a carrier of sine wave form and for effecting locked synchronism of one oscillator with the fundamental or a harmonic of another oscillator.

5 Among the several objects of my invention are:

To provide a simple and effective means for frequency modulating a sine wave carrier over wide limits with an unusually high degree of 10 linearity;

To provide a frequency shift oscillator of high sensitivity;

To provide means for easily adjusting the 15 average frequency of a sine wave frequency modulated carrier by shifting either the value of the tuning elements or by changing the value of a biasing voltage or supply voltage, without impairing the power of the oscillator that is frequency modulated;

20 To provide means for frequency division;

To provide means for non-synchronous frequency control.

The means for accomplishing the foregoing 25 objects together with others that will subsequently appear are shown in the annexed drawing wherein:

Fig. 1 depicts a vacuum tube network embodying a satisfactory form of my invention;

Fig. 2 shows graphically the relation between 30 frequency and grid voltage under different voltage conditions on certain tube elements;

Fig. 3 shows graphically the relation, at present considered optimum, between plate voltage and suppressor grid voltage;

35 Fig. 4 illustrates the conditions under which synchronous frequencies may be locked together;

Fig. 5 shows graphically the conditions for non-synchronous frequency control.

Examination of the static characteristics of a 40 small pentode radio receiving tube such as the type '57 or 6C6 shows that when the suppressor grid is negative with respect to the cathode potential, negative mutual conductance exists between the screen grid as the anode, and the suppressor grid as the control grid, when the first, or regular, control grid is kept at constant potential. In this condition oscillations can occur in a LCR circuit in the screen grid lead, provided coupling is established between screen grid 45 and suppressor grid circuits that will swing the suppressor in phase with the screen grid acting as anode.

50 Referring to Fig. 1, the tube 6 has an anode 1,

is connected to cathode 8 through an impedance 12, lead 13 and resistance 14 which provides the negative bias for the suppressor grid 11. Condenser 15 in parallel with resistance 14 aids in filtering the suppressor grid supply. Screen grid 10 is connected to +B supply lead 16 through impedance 17 and to the high potential side of resistance 14 by variable condenser 18, the impedance 17 and condenser 18 constituting an oscillatory circuit associated with screen grid 10. The screen grid oscillatory circuit is coupled to suppressor grid 11 by condenser 19 to cause suppressor grid 11 to swing in phase with the screen grid 10. Variable bias is impressed upon control grid 9 through variable resistance, or potential divider 20 with filtering by condenser 21 in parallel with the potential divider. Control voltage input is by means of transformer 22 whereof the secondary is connected to grid 9 and potential divider 20. The transformer 22 is shown as an audio frequency transformer for purposes of illustration since one application of this invention has been voice modulation of frequency through a carbon button microphone directly connected to the primary of transformer 22 without amplification between the microphone and the transformer. The network is coupled to the next stage by condenser 23.

Operation of this network showed that the 30 oscillating frequency was of almost pure sine wave form, as observed on the cathode ray oscilloscope, and by harmonic analysis of the wave form itself. It was also observed that the frequency of oscillation thereof changed when the voltage on the control grid was varied. It was then obvious that if the frequency change of the oscillator in response to fluctuating control grid voltages were anything approaching a linear function of the control grid voltage, the apparatus could be used as a frequency modulator 35 for a radio frequency carrier. A test of the frequency characteristics was made with 12, 17 and 24 having values of 2.5 millihenries, 19 having a capacity of 250 micromicrofarads and 18 having zero capacity, under the conditions given in 40 45 the following table:

Curve	Plate volts— screen volts	Suppressor volts
1	122	-32
2	100	-26
3	62	-15
4	42	-9

quency variation produced by the several control grid voltages given as abscissae in Fig. 2 when the voltages on the screen grid and the suppressor grid had the values given in the table. It will be noted that, in general, the absolute value of the screen grid voltages given in this table are substantially four times the absolute value of the suppressor grid voltages. The optimum relation of screen grid voltages to suppressor grid voltages is shown in the graph of Fig. 3, which corresponds essentially to the relations set forth in the table. It was found that oscillations in the circuit occurred with highest amplitude and persisted over the greatest range of frequency when the voltage relations were as above defined.

It will be noted that the frequency shift is considerable for a small change of control grid voltage. When this oscillator was fed by a carbon button microphone through transformer 22 it was observed that sufficient frequency swing was produced to effect satisfactory frequency modulation without amplification between the microphone and the transformer, a maximum shift of ± 10 kilocycles being obtained with no observable distortion of quality.

Due to the inherent frequency sensitivity of this circuit, it appeared that it might be used as a locked frequency oscillator. A synchronous frequency was introduced into the control grid circuit, and at very small amplitude immediately locked the two together. Fig. 4 shows this effect for two different set-ups of screen grid and suppressor grid voltage with a bias of two volts on the control grid. The voltages applied to the control grid are given as the abscissae and the frequencies of the control voltages are shown as ordinates. It will be noted from the solid line graph in Fig. 4 that one-tenth volt rms signal applied to the control grid could lock in an oscillator of the above type that was within ± 25 kilocycles of the applied signal frequency and that one-half volt could "drag" it as far as 100 kilocycles, amounting to about a 15 per cent frequency "drag" for one-half volt input.

In one case, the control voltage was modulated 40 per cent with 1000 cycles. The carrier controlled the oscillator within the above limits but as soon as the control frequency passed beyond the control range one of the modulation sidebands took charge, namely the sideband nearest the locked oscillator's free frequency and maintained control until the frequency got beyond its range. It has been found that the control voltage may be introduced in series with impedances 52 and 17 with equally good results except when the circuit is used as a frequency changer.

Another use of this invention is as a non-synchronous frequency control. A control frequency substantially different from the free frequency of the oscillator, but of the same order of magnitude, is impressed on the control grid. Variation of the amplitude of this signal changed the oscillator frequency in the direction of the control frequency, as shown in Fig. 5. For example, when the frequency difference was no greater than 20 kilocycles the oscillators locked together at 0.45 volt control. However, this variation of frequency is not linear with applied amplitude and so it could not be used for conversion of amplitude modulation to frequency modulation without correction. It is to be noted, however, that in all of the above described uses and tests frequency modulation occurred without change of amplitude of the oscillation.

The frequency of the oscillations is a function

of applied voltage (other than the control grid voltage) which allows adjusting the free frequency by a number of means. It also suggests the use of the circuit to control the voltage of a circuit by interpreting properly the frequency of the oscillator and feeding back the output to control the input voltage. For reception of frequency modulated waves, this circuit can be locked with the incoming carrier, to effect a substantial amplification and automatic volume control and static elimination.

For a cathode ray oscillograph driver for visual checking of band pass characteristics of networks and radio receivers a sine wave voltage (preferably 60 cycles) is applied to the horizontal deflecting plates of the cathode ray tube and also to the control grid of the oscillator in phase or 180° out of phase. By adjusting the magnitude of the swing on the grid, the limits of frequency shift are under control. Changing the value of condenser 18 will adjust the oscillator frequency to the proper point. If the detected output of the network be applied to the vertical deflecting plates, a graph of the frequency characteristic is drawn on the face of the cathode ray tube with a perfectly linear horizontal frequency scale.

Illustrative of the range of utility of this invention, the following uses to which it has been put may be enumerated:

- (a) Voice modulation for radio communication.
- (b) Frequency division.
- (c) Locked synchronous oscillations.
- (d) Voltage regulators.
- (e) Current regulators.
- (f) Reception of frequency modulated carriers.
- (g) Band pass driver for cathode ray oscilloscope sweep circuit.
- (h) Non-synchronous frequency control.

According to the provisions of the patent statutes I have set forth the principle and mode of operation of my invention and have illustrated and described what I now consider to represent its best embodiment. However, I desire to have it understood that within the scope of the appended claims the invention may be practiced otherwise than as specifically illustrated and described.

The invention herein described and claimed may be used and/or manufactured by or for the Government of the United States of America for governmental purposes without the payment of any royalties thereon or therefor.

I claim:

1. A vacuum tube having an anode, a cathode, a control grid, a screen grid and a suppressor grid; a positive and a negative potential supply lead, means including a highly reactive first inductance connecting said anode to said positive supply lead, a second highly reactive inductance connecting said suppressor grid to said negative supply lead, a first resistance connected in series between said cathode and said negative supply lead and to said second inductance whereby the potential drop due to current in said resistance holds said suppressor grid negative with respect to said cathode, means including a third inductance connecting said screen grid to said positive supply lead, a first capacitance tightly coupling said screen grid to said suppressor grid to cause potential variations on said suppressor grid to occur in phase with potential variations on said screen grid, a small second capacitance connecting said screen grid to said cathode, said third inductance and said second capacitance cooperating with the tube elements respectively connected

thereto to constitute a self-oscillatory circuit, an output circuit connected to said cathode and to a point between said anode and said first inductance, means connecting said control grid to said cathode to apply bias potentials to said control grid, and means to apply varying potentials to said control grid to effect frequency modulation of the output of said tube.

2. A vacuum tube having an anode, a cathode, a control grid, a screen grid and a suppressor grid; a positive and a negative potential supply lead, means including a first inductance connecting said anode to said positive supply lead, a second inductance connecting said suppressor grid to said negative supply lead, means to derive a potential drop from current through said tube and apply said drop to said suppressor grid to keep said suppressor grid negative with respect to said cathode, means including a third inductance connecting said screen grid to said positive supply lead, a first capacitance coupling said screen grid to said suppressor grid to cause potential variations on said suppressor grid to occur in phase with potential variations on said screen grid, a second capacitance connecting said screen grid to said cathode, said third inductance and said second capacitance cooperating with the tube elements respectively connected thereto to constitute a self-oscillatory circuit, means connecting said cathode to said control grid to apply biasing potentials to said control grid and means to apply varying potentials to said control grid to effect frequency modulation of the output of said tube.

3. A vacuum tube having a cathode, an anode, a control grid, a screen grid and a suppressor grid; a supply lead connected to said anode, a resistance connected to said cathode, means including an inductance connecting the side of said resistance remote from said cathode to said suppressor grid to maintain said suppressor grid at a potential lower than the potential of said cathode, a condenser connected across said resistance, means including elements constituting an oscillatory circuit connecting said screen grid to the side of said resistance adjacent said cathode and to said anode supply lead, a coupling capacitance connecting said screen grid to said suppressor grid, a capacitance having one side connected to the side of said inductance remote from said suppressor grid and its other side connected between said oscillatory circuit and said anode lead, an input circuit including adjustable biasing means connected to said control grid, and an output circuit connected to said anode.

4. A vacuum tube having a cathode, an anode, a control grid, a screen grid and a suppressor grid, means to develop a potential drop by current through said tube to maintain said suppressor grid at less than cathode potential, an oscillatory circuit connected to said screen grid and to said cathode, means coupling said suppressor grid to said screen grid to cause said suppressor grid to swing in phase with said screen grid, an input circuit connected to impress varying voltages upon said control grid to effect frequency modulation of the output of said tube and an output circuit connected to said anode and said cathode.

5. The method of frequency modulation of a radio wave in a system including a vacuum tube having an anode, a cathode, a control grid, a screen grid, and a suppressor grid, said screen grid and said suppressor grid being coupled into self-oscillatory relation, which comprises the steps of applying substantially the same value of

potential to said screen grid as applied to said anode, maintaining said suppressor grid at a potential less than the potential on said cathode, maintaining an oscillatory condition between said screen grid and said suppressor grid, and applying modulating potentials to said control grid. 5

6. The method of frequency modulation of a radio wave in a system including a vacuum tube having an anode, a cathode, a control grid, a screen grid, and a suppressor grid, said screen 10 grid and said suppressor grid being coupled into self-oscillatory relation, which comprises the steps of applying a substantial positive potential to said screen grid, maintaining said suppressor grid at less than cathode potential, maintaining 15 an oscillatory condition between said screen grid and said suppressor grid, and applying modulating potentials to said control grid.

7. The method of frequency modulation of a radio wave in a system including a vacuum tube 20 having an anode, a cathode, a control grid, a screen grid, and a suppressor grid, said screen grid and said suppressor grid being coupled into self-oscillatory relation, which comprises the steps of applying a substantial positive potential to said 25 screen grid, the absolute value of the positive potential on said screen grid being substantially four times the absolute value of the negative potential on said suppressor grid, maintaining said suppressor grid at less than cathode potential, 30 maintaining an oscillatory condition between said screen grid and said suppressor grid, and applying modulating potentials to said control grid.

8. A method of operating a space discharge system having a zone wherein electrons are released and spaced therefrom an output zone wherein electrons are absorbed, comprising the steps of maintaining between said zones a first potential zone to control the electron stream, a second potential zone wherein the potential is 40 substantially that of said output zone, and a third potential zone wherein the potential is substantially less than that of said zone of release of electrons, effecting self-oscillatory variations of potential in phase in said second and third zones, 45 the absolute value of potential in said second zone being about four times that of the potential in said third zone, and applying in said first zone varying potentials, whereby the frequency in said output zone is varied as a linear function of said 50 varying potentials in said first zone.

9. A method of operating a space discharge system having a zone wherein electrons are released and spaced therefrom an output zone wherein electrons are absorbed, comprising the 55 steps of maintaining between said zones a first potential zone to control the electron stream, a second potential zone wherein the potential is substantially that of said output zone, and a third potential zone wherein the potential is 60 substantially less than that of said zone of release of electrons, effecting self-oscillatory variations of potential in phase in said second and third zones, and applying in said first zone varying potentials, whereby the frequency in said 65 output zone is varied as a linear function of said varying potentials in said first zone.

10. A method of operating a space discharge system having a zone wherein electrons are released and spaced therefrom an output zone 70 wherein electrons are absorbed, comprising the steps of maintaining between said zones a first potential zone to control the electron stream, a second potential zone wherein the potential is substantially that of said output zone, and a 75

third potential zone wherein the potential is substantially less than that of said zone of release of electrons, effecting self-oscillatory variations of potential in phase in said second and third zones, 5 the absolute value of potential in said second zone being about four times that of the potential in said third zone, and applying in said first zone varying potentials of a frequency differing from the free frequency of the oscillatory 10 potentials between said second and third zones but of the same order of magnitude, and varying the amplitude of said applied varying potentials, whereby the frequency of said oscillatory variations is brought into synchronism with that of 15 said applied potentials.

11. A vacuum tube having a cathode, an anode, a control grid, a screen grid and a suppressor grid, means to maintain said suppressor grid at less than cathode potential, a series resonant 20 circuit connected to said screen grid and to said cathode, means coupling said suppressor grid to said screen grid to cause said suppressor grid to swing in phase with said screen grid, an input circuit connected to said control grid and to said 25 cathode and an output circuit connected to said anode and to said cathode.

12. A vacuum tube having a cathode, an anode, a control grid, a screen grid and a suppressor grid, means to impress a positive potential on said screen grid, means to impress a negative potential on said suppressor grid, the absolute value of said positive potential being substantially four times the absolute value of said negative potential, a series resonant circuit connected to said screen grid and to said cathode, and means coupling said screen grid to said suppressor grid 10 to cause them to swing in phase. 5

13. A vacuum tube having a cathode, an anode, a control grid, a screen grid and a suppressor grid, a lead to supply positive potential to said anode, a series resonant circuit connected 15 between said lead and said cathode, means connecting said screen grid to said resonant circuit, means to impress on said suppressor grid a negative potential whereof the absolute value is approximately one-fourth the absolute value of the 20 positive potential on said screen grid, and means coupling said screen grid and said suppressor grid to cause them to swing in phase. 25
